UNITED STATES PATENT OFFICE.

EDWIN P. JONES, OF PORT TOWNSEND, WASHINGTON.

CAN-SORTING MACHINE.

1,115,829.

Specification of Letters Patent.

Patented Nov. 3, 1914.

Application filed February 2, 1914. Serial No. 815,926.

To all whom it may concern:

Be it known that I, EDWIN P. JONES, a citizen of the United States, residing at Port Townsend, in the county of Jefferson and 5 State of Washington, have invented certain new and useful Improvements in Can-Sorting Machines, of which the following is a specification.

This invention relates to weight-sorting 10 machines.

The object of the invention is to produce an inexpensively constructed and efficient machine for successively weighing canned goods fed to the machine which will reject 15 the cans whose weights are below the standard to which the balance scale of the machine is adjusted.

The invention consists in the novel construction and combination of parts, as will 20 be hereinafter described and claimed.

In the accompanying drawings, Figure 1 is a view shown partly in side elevation and partly in longitudinal vertical section of a machine embodying my invention. Fig. 2 is 25 a plan view of the same. Fig. 3 is a perspective view of the balance scale and the controlling devices therefor. Fig. 4 is a sectional view through 4—4 of Fig. 2. Fig. 5 is a sectional view through 5—5 of Fig. 4.

30 The frame of the machine is provided with an inclined feed chute 5 down which the cans roll by gravity to a weighing pan 6 and beyond the latter is an inclined discharge chute 7 by which cans of standard 35 weight, or greater, roll from the pan. The chutes 5 and 7 are connected by side members 8 of the frame which are spaced apart to accommodate the scale-pan therebetween. Positioned below the chute 7 is a second inclined delivery chute 9 for light-weight cans 40 which are deposited thereon from the pan.

Provided in the feed chute 5 is a spacing device comprising a pair of star-wheels 10 mounted upon a shaft 11 and intermittently rotated by means of a sprocket-chain 12 passing about a sprocket-wheel 13 on said shaft and a sprocket-wheel 14 on a shaft 15 which is positioned below the pan 6. Provided on shaft 15 is a feed-wheel having a 45 plurality of radially disposed arms 16 which revolve through a longitudinal slot 17 provided in pan 6 for the purpose of regulating the travel of the cans as they traverse the pan. The relative sizes of the sprocket

wheels 13 and 14 are such as to afford motion to the star-wheels to deliver a can to the pan 6 as each of the feed-wheel arms is presented.

18 and 19 represent shafts journaled in bearings which depend from the chutes 7 and 9. Mounted on the shaft 18 is a sprocket-wheel 20 serving as a driver for a chain 21 which passes about a sprocket-wheel 22 mounted on shaft 15 to rotate the same only when the chain is driven in the direction indicated by arrow *x* in Fig. 1; to which end, I secure a ratchet-wheel 23 to the shaft 15 and within a cylindrical chamber provided in the body of the wheel 22, and having balls or rollers 24 provided in the gullets of the ratchet wheel to engage with the peripheral surface of said chamber when the ratchet-wheel is turned in the direction corresponding to arrow *X* and becoming inoperative when the ratchet wheel 75 is turned in a contrary direction. In like manner, a chain 25 is employed to transmit motion from a driving wheel 26 on shaft 19 to a sprocket-wheel 27 provided on shaft 15. The wheel 27 has clutch devices therein 80 similar to those illustrated and described for the wheel 22 to afford motion to the shaft 15 only when the chain 25 is driven as indicated by arrow *Y*, Fig. 1.

Wheels 18¹ and 19¹ are provided on the 85 shafts 18 and 19 and are provided with arms which revolve within the paths of cans in rolling down the discharge chutes so as to be successively encountered by the cans which in passing the wheels 18¹ or 19¹ impart a partial rotation thereto sufficient to furnish the requisite amount of movement to the shaft 15 carrying the feed-wheel and the shaft 11 which carries the star-wheels.

The pan 6 is hingedly supported from 95 near its forward end to pins 28 provided on the lower ends of the side members 29 of a yoke 29¹.

Extending through the yoke 29¹ are screws 30 which have their lower ends fit into depressions 31 provided in the upper sides of arms 32 which are rigidly secured to and extend forward from a transversely arranged beam 33. The beam is provided at its ends with pivotal supports or projections, such as 34, (Fig. 3) which are seated in apertures provided in posts 35 extending upwardly from the machine frame.

Extending rearwardly from the beam 33 is an arm 36 upon which is adjustably secured a scale-weight 37.

Secured intermediate its length to each of 5 the yoke members 28 is a longitudinal bar 38 which supports at its forward end a rod 39 having at its lower end an inwardly directed finger 40 extending under the pan to prevent the front of the latter from 10 tilting down below a horizontal plane. The referred to end of the pan is normally held to rest upon fingers 40 through the agency of weights 41 attached to the underside of the pan. The rear ends of the bars 38 have 15 pivotally connected thereto by screws 42 levers 43, each of which has an arm 44 provided with a finger 44¹ arranged to be swung beneath the rear end of the pan by means of a weight 45 provided on the lever-arm 46, 20 a third arm 47 extending upwardly and thence laterally to beneath the arm 36 of the scale-beam.

48 represents studs provided in posts 35 to limit the downward movements of the 25 forward ends of the bars 38.

The operation of the machine is as follows: The cans to be assorted are placed in the chute 5 and roll down by gravity against the star-wheels 10 so that as the latter are 30 given intermittent rotary motion, the cans are transposed beyond the star-wheels to roll onto the scale-pan 6. Should the weight of the can be sufficient to over-balance the weight 37, then the pan will be depressed 35 resulting in the arms 32 being tilted down and the other arm 36 being tilted up. When this occurs, the power of the weights 45 asserts itself to influence the levers 43 so as to thrust the fingers 44¹ thereof below the 40 rear end of the scale-pan 6 and prevent the same tilting down into the position indicated by broken lines 6^a when the can is brought to that end of the scale-pan through the agency of an arm of feed-wheel 16. 45 The fingers 44¹ respond to the action of the scale-lever 32—36 and weights 45 when influenced by a can of suitable weight, so that the scale-pan is arrested against tilting before the pan gets below the runway for the 50 cans in chute 7. A can of standard weight or more will thus automatically effect the locking of the scale-pan against tilting and will be delivered into the upper end of the discharge chute and rolling down the same 55 run against one of the arms of wheel 18' and by its momentum cause the same to be turned sufficiently to impart motion to the chain 21 whereby the shaft 15 is partially rotated to rotate in turn the shaft 11 60 through the medium of the driving mechanism therebetween. The shafts 11 and 15 being thus turned regulate the timed delivery of the cans to the pan 6 and the movement of the can over the scale by the star-wheels 10 and the wheels 16. It may be

mentioned that in starting, an attendant operates the chain 21 with his hand until the first can has traveled over the pan, but thereafter the machine will be automatic while cans are supplied to the feed-chute 5. 70

In case of a can weighing less than is required to overcome the power of the weight 37, the lever-arms 47 are prevented from raising, hence the fingers 44¹ remain in inoperative positions and when the light can 75 reaches the rear end of the pan, the pan will be tilted into the position indicated by 6^a and will deposit the can on the chute 9. The can thereupon rolls down the chute and causes the wheel 19¹ to be turned to operate 80 the star- and feed-wheels to perform their duties. After a light can has been discharged from the pan 6, the same is restored to its horizontal position by means of weights 40. 85

What I claim as my invention, is—

1. In a weight-sorting machine, the combination with the machine frame provided with a feed-chute, and two superposed inclined discharge-chutes, of a scale-pan interposed between said feed-chute and the higher of the discharge-chutes, a scale balance for said pan, means regulated by the weight of articles being weighed on the pan whereby the full-weight articles are delivered upon 90 the higher discharge-chute and articles of less weight are delivered to the lower chute. 95

2. In a weight-sorting machine having a frame provided with two discharge chutes, a scale balance, a tiltable pan suspended 100 from one end thereof, means for feeding articles to said pan, means for causing said articles to traverse said pan, means controlled by said balance when influenced by articles when upon the pan whereby the latter is maintained in position to deliver the articles above a definite weight to one of 105 said chutes, and articles of less weight are rendered capable to tilt the pan and thereby be discharged in the other chute. 110

3. In a weight-sorting machine, a scale balance having a tiltable pan which is adapted to be depressed by an article of sufficient weight, means to effect the traverse movement of articles to be weighed across the 115 pan, means actuated by the depression of the pan whereby the latter is positively prevented from tilting so that such article will be discharged in a substantially horizontal direction from the pan, and articles having 120 less weight than required to depress the pan will tilt the latter and cause such article to thereby be deposited below the pan. 125

4. In a weight-sorting machine, a gravity feed-chute, and two gravity-discharge chutes, a scale balance having a tiltable pan, means actuated by the weight of cans passing down either of said discharge chutes whereby the cans are successively fed to the pan and then caused to traverse the pan, and 130

means controlled by a can while upon the pan whereby cans of sufficient weight to depress the pan are delivered into one of said discharge-chutes and light-weight cans are delivered into the other discharge-chute.

5. A weight-sorting machine, comprising a scale-balance provided with a tiltable weighing-pan which is adapted to be depressed by an article of sufficient weight, 10 means to feed cans to said pan, a discharge-chute at one end of the balance, and means actuated by the depression of the pan whereby the latter is positively prevented from tilting whereby such cans are delivered to 15 said chute while cans of lighter weight are dumped from the pan by tilting the same.

6. In a can-sorting machine, a scale-balance, means coöperating with said balance whereby cans are supplied to the balance for 20 successively weighing the same, means to progressively move the cans over the top of and discharge the same from the pan of said balance, and devices actuated by the cans subsequent to their being discharged from 25 the pan whereby the aforesaid means are operated.

7. In a can-sorting machine, a scale-beam, a tiltable pan supported from one side of said beam and a weight secured to the other 30 side thereof, and devices carried by said beam and rendered operative by an article on the pan of sufficient weight to overbal-

ance the aforesaid weight whereby the pan is positively prevented from tilting.

8. In a can-sorting machine, a scale-beam, 35 a tiltable pan supported from one side of said beam and a weight secured to the other side thereof, levers operatively connected with the beam and provided with fingers which are caused to be swung below the pan 40 to prevent the same from tilting when the pan is depressed by an article having sufficient weight to overbalance the first-named weight.

9. In a can-sorting machine, a scale-balance having a tiltable pan, means to supply articles whose weights are to be tested to the pan and over the same, said pan being arranged to be tilted by an article of less weight than that to which the balance is adjusted for the purpose of dumping such light-weight articles from the pan, means for restoring the pan to its normal horizontal position, and means operated by an article of sufficient weight to overbalance the 55 scale whereby the scale-pan is temporarily prevented from tilting.

Signed at Seattle, Wash., this 23rd day of January, 1914.

EDWIN P. JONES.
